UNITED STATES PATENT OFFICE.

HENRY T. CLAWSON, OF NEWARK, NEW JERSEY.

DESIGN FOR A MONUMENT.

SPECIFICATION forming part of Design No. 22,476, dated May 30, 1893.

Application filed July 30, 1892. Serial No. 441,752. Term of patent 14 years.

To all whom it may concern:

Be it known that I, HENRY T. CLAWSON, a citizen of the United States, residing at Newark, in the county of Essex and State of New Jersey, have invented and produced a new and original Design for a Monument, of which the following is a full, clear, and exact description.

The new design is shown in the accompanying drawing which is a perspective view of a monument embodying the same.

The design comprises as its leading features the figure of a child A with eyes cast downward and hands stretched downward and outward seated lightly with the legs to one side on a sphere B, and an eight-sided pedestal C with a frusto-pyramidal top C' on which is sphere B. The pedestal and frusto-pyramidal top have raised panels c and c' respectively and are divided from each other by the horizontal projecting rib or cornice c*. The base

of the pedestal consists of the eight sided slabs or blocks D and E.

The design not only consists in the shape or configuration of the monument as a whole, but comprises also the childish figure, and the pedestal with its frusto-conical top and panels, severally and each in connection with the sphere.

I claim—

1. The design for a monument herein shown and described.
2. The design of the childish figure in the monument shown and described.
3. The design of the pedestal in the monument shown and described.

In testimony whereof I have signed this specification in the presence of two witnesses.

HENRY T. CLAWSON.

Witnesses:

WILLIAM WAKEMAN,
S. PERIT RAWLE.
